UNITED STATES PATENT OFFICE.

ENOCH MOORE, JR., OF WILMINGTON, DELAWARE.

GOLF-CLUB CARRIER.

Application filed January 16, 1922. Serial No. 529,772.

To all whom it may concern:

Be it known that I, ENOCH MOORE, Jr., a citizen of the United States, residing at Wilmington, in the county of New Castle 5 and State of Delaware, have invented certain new and useful Improvements in Golf-Club Carriers; and I do declare the following to be a full, clear, and exact description of the invention, such as will enable others skilled in the art to which it appertains to 10 make and use the same.

This invention relates to a golf club carrier and one object of the invention is to provide a carrier so constructed that it may be placed flat upon the ground if so desired or rolled to provide a substantially tubular structure, the body forming strip having pockets upon one side which may be positioned internally or externally of the tubular structure when rolled so that the golf clubs may be positioned within the tubular structure or externally thereof as desired.

Another object of the invention is to so construct this carrier that the body forming 25 strip may be formed from a strip of flexible material such as khaki cloth, canvas or the like, and the pockets in which the clubs are to be carried formed from a strip of similar material which will be placed against one 30 face of the body forming strip and secured thereto by stitching which will serve to secure the pocket-forming strip to the body strip and further serve to divide the pocket-forming strip into club-receiving pockets 35 which extend longitudinally of the body strip.

Another object of the invention is to so construct this carrier that the body-forming strip will extend beyond the upper end of 40 the pocket-forming strip and thus provide a flap portion which will be foldable to extend over and form a cover or closure for the open upper ends of the pockets.

Another object of the invention is to so 45 construct this carrier that the side edge portions of the body forming strip may be releasably connected in forming the tubular structure and to further so construct the carrier that securing straps may be passed about 50 the tubular structure to securely hold it rolled with the flap turned downwardly to cover the pockets which will be positioned internally when the encircling straps are in use.

55 Another object of the invention is to so construct this carrier that a shoulder strap

may be secured against one face of the body strip and doubled back and connected with a buckle upon the same face of the body-forming strip; or the strap can be passed 60 through an opening formed in the body-forming strip adjacent the upper end of the pocket-forming strip and then doubled back and connected with a buckle thus permitting the same shoulder strap to be used 65 with the carrier rolled to position the club-receiving pockets internally or externally.

Another object of the invention is to provide a club carrier which is so constructed that the portion carrying the pocket-forming strip may be braced by strips which extend longitudinally of the structure and thus 70 this portion of the carrier braced against crumpling.

Another object of the invention is to provide a golf club carrier which will be light in weight, and very strong and durable, and very convenient for use.

This invention is illustrated in the accompanying drawings, wherein:

Figure 1 is a view showing the carrier placed flat with the pocket side uppermost.

Figure 2 is a view similar to Fig. 1 showing the opposite side uppermost.

Figure 3 is a view showing the upper portion of the device positioned as shown in Fig. 1 with the flap turned down to cover the upper end portions of the pockets.

Figure 4 is a perspective view showing the carrier rolled with the pockets positioned internally thereof.

Figure 5 is a transverse sectional view taken along the line 5—5 of Fig. 1.

Figure 6 is a sectional view taken along the line 6—6 of Fig. 1.

Figure 7 is a sectional view taken along the line 7—7 of Fig. 1.

This golf club carrier will be formed principally from two strips of khaki cloth or any other suitable flexible material, one of 100 which will be termed the body strip and indicated in general by the numeral 1 and the second of which will be termed the pocket-forming strip and indicated in general by the numeral 2. This pocket-forming strip 2 105 is placed upon the body strip 1 and has its edge portion sewed to the body strip. The pocket-forming strip in the form shown will be wider than the body-forming strip before being put in place and between the side 110 edges which are sewed to the body-forming strip, this pocket-forming strip will be

sewed to the body-forming strip by longitudinally extending lines of stitching which serve to assist in holding the pocket-forming strip upon the body strip and further 5 serves to divide this pocket-forming strip into a plurality of pockets which are indicated by the numerals 3. By having the pocket-forming strip relatively wide and sewed to the body-strip with its side edge 10 portions secured within the width of the body strip and the pocket-forming strip then secured at points throughout its width by lines of stitching which extend longitudinally of the body-forming strip and 15 pocket-forming strip, the pockets 3 will be relatively baggy and will extend out from the body strip so that the golf clubs can be very easily placed in these pockets. From an inspection of Fig. 1, it will be readily 20 seen that the body strip 1 extends beyond the upper end of the pocket-forming strip and therefore provides a flap forming extension 4 which may be folded down as shown in Fig. 3 to cover the upper ends of 25 the pockets. A binding 5 which is preferably formed of a relatively tough material such as soft leather is provided for the edges of the body strip at the sides and tops thereof and a binding strip 6 which is formed 30 of thicker leather is provided for the lower edges of the body-forming strip and pocket-forming strip so that the device may more readily rest upon the ground and be protected from quickly wearing out. It is further desired to strengthen the carrier from 35 the lower end thereof to the upper end of the pocket-forming strip so that the carrier cannot crumple when placed upon the ground as shown in Fig. 4. Therefore, there has 40 been provided reinforcing strips or stiffener strips 7 formed of compressed fibre or any suitable material which will provide a strengthening strip having sufficient strength to prevent crumpling of the carrier but at the same time have sufficient elasticity to prevent danger of the strips being 45 readily broken. These strips 7 are placed longitudinally upon the body strip 1 upon the opposite face thereof from the pocket-forming strip 2 and are held in place by 50 strips of fabric tape 8 which are sewed to the body strip as shown in Fig. 5 and secured at their ends by rivets 9. A cross strip 10 which is formed of leather extends 55 across the body-forming strip and is secured thereto by rivets 11 which pass through this leather strip 10 and also pass through the upper ends of the reinforcing strips 7. Tabs 12 are provided to strengthen the upper end 60 portions of the pockets and prevent them from being torn loose, these tabs 12 being formed of leather and secured by stitching and by means of rivets 13. In order to provide for releasably holding the cover flap in 65 the folded or closed position shown in Fig. 4, there has been provided eyes 14 and studs 15, the eyes 14 being carried by the flaps and the studs 15 being secured to the pockets and adapted to be passed through the eyes and then turned to the locking position. It 70 is of course obvious that these eyes and studs are only a conventional showing of fastener and that fasteners of a modified construction could be made use of if so desired. 75

By having the carrier formed as shown, it can be placed flat upon the ground or upon a table or other suitable support and the golf clubs can then be easily placed in the pockets 3. The golf balls will be placed 80 in pockets 16 which are sewed to the pocket-forming strip adjacent the lower end thereof and provided with cover flaps 17. Fasteners 18 similar to the fasteners 15 are provided upon the pockets 16 and will be 85 passed through eyes 19 carried by the flaps 17 and turned to secure the flaps in the closed position as shown in Fig. 6. When the golf balls and golf clubs are in place, the cover strip or flap 4 will be turned down 90 and fastened as shown in Fig. 3 and the carrier will then be rolled with the pockets positioned internally and the side edge portions of the body strip can be connected by the fasteners 20 being passed through the 95 eyes 21 and then turned to the locking position. The straps 22, 23 and 24 can then be passed around the rolled carrier and secured by means of the buckles shown. It should be noted that one of these buckles which is 100 indicated by the numeral 25 is provided with a lock structure so that when the strap is fastened, it cannot be released until the lock has been released. It is obvious that each 105 of the straps may be provided with similar buckles if so desired. It is also obvious that if it is found preferable, the carrier may be rolled without the side portions being connected by the fasteners 20 and eyes 21 with the side portion which carries the straps 110 positioned externally and extending in overlapping relation to the remainder of the roll and the straps then placed about the roll and secured. A hand grip 26 is provided intermediate the straps 22 and 23 so that 115 the carrier can be very easily carried. It is further desired to provide a shoulder strap so that the carrier may be suspended from the shoulder when being carried to the links and while in use. There has therefore been provided a shoulder strap 27 which is secured to the side edge portion of the body-forming strip and extends longitudinally over one of the reinforcing strips 7. A reinforcing pad which is formed of 120 leather is positioned beneath the strap 27 as shown in Fig. 7 and one of the rivets 13 serves to firmly secure this strap in place. Alined openings are formed in the strip 10, tab 28 and the portion of the strip 1 be- 125 130

tween these openings thus providing a passage 29 so that if desired the strap may be passed through this passage and projected externally of the rolled carrier when the 5 carrier is rolled with the pockets positioned internally thereof. In order to provide a loop of the strap so that the bag can be conveniently suspended from the shoulder, there has been provided buckles 30 and 31, 10 one of which is provided upon the face of the body-forming strip 1 to which the pocket-forming strip is secured, and the other of which is secured upon the strip 8 upon the opposite face of the body forming 15 strip. It will thus be seen that the free end portion of the strap 27 can be connected with either one of these buckles according to the manner in which the carrier has been rolled.

20 When the golf sticks are to be used, the straps 22, 23 and 24 will be released and the carrier can then be unrolled. The flap 4 will then be released and swung to an open position and swung downwardly so that it 25 hangs free from the carrier at the upper end of the pocket-forming strip. The carrier can then be again rolled and the side edge portions connected by means of the fasteners 20 and eyes 21. If the carrier is 30 rolled with the pockets positioned internally, the strap 27 will be passed through the passage 29 and will have its free end portion connected with the buckle 31 and if desired the straps 22, 23 and 24 may be secured 35 about the rolled carrier but this is not necessary and will only be done to prevent the straps 22, 23 and 24 from getting in the way. If the player desires to use a certain club, thus club can be easily removed from 40 its pocket and after being used, can be very easily put back in place. By rolling the carrier with the pockets externally instead of internally, the carrier will have the same cylindrical shape disclosed in Fig. 4 but 45 when this is done, the pockets will be positioned externally of the cylindrical carrier and the clubs will be exposed to view where they can be very readily removed and very easily put back in the pockets. When the 50 carrier is rolled with the pockets positioned externally thereof, the strap 27 will not be passed through the passage 29 and will be connected with the buckle 30 instead of with the buckle 31. The straps 22, 23 and 24 will 55 then be positioned within the carrier and of course will not be secured about the carrier. There has thus been provided a golf club carrier which is so constructed that it may be placed flat when the golf clubs are to be 60 put away for future use and then a cover flap folded downwardly to cover the open upper ends of club-receiving pockets and the carrier then rolled into a compact mass. It will be further noted that there has been 65 provided a golf club carrier so constructed

that when in use it may be formed into a tubular structure having the club-receiving pockets positioned internally or externally thereof. It will be further noted that there has been provided a golf-club-carrier which 70 can be formed of khaki cloth, canvas or other suitable material and will be light in weight and at the same time very strong and durable.

I claim:

1. A club carrier comprising a flexible body having its side portions provided with means for releasably connecting the edges to provide a tubular structure open at its upper and lower ends, and club-receiving pockets extending longitudinally of the flexible body from a point adjacent its lower end to a point in spaced relation to its upper end and open at their upper ends and closed at their lower ends.

2. A club carrier comprising a flexible body strip rollable to form a tubular structure open at its upper and lower ends and having means for releasably connecting the edges of said strips when rolled, and pockets 90 extending longitudinally of the body strip, the body strip having its upper end portion extended to provide a flap foldable to extend over and close the upper ends of the pockets.

3. A club carrier comprising a flexible body strip rollable to form a tubular structure and having its edge portions provided with means for releasably connecting the said edges when rolled, a pocket-forming 100 strip fitting against one face of the body strip and having fastener means securing the pocket-forming strip to the body strip and dividing the pocket-forming strip into longitudinally extending pockets, the body 105 strip having a flap extension for covering the open upper ends of the pockets.

4. The structure of claim 2 and strengthening strips extending longitudinally of the body strip to hold the pocket carrying portion thereof against doubling longitudinally.

5. A club carrier comprising a flexible body having its side portions provided with means for releasably connecting the edges to provide a hollow carrier open at its upper 115 and lower ends, the flexible body being provided with an opening adjacent one edge, means carried by the body for holding clubs placed longitudinally thereof, a carrier strap secured to one face of the body and projectable through the opening, strap engaging means upon one face of the body strip for engaging the strap when projected through the opening, and strap engaging means upon the other face of the body strip for engaging 125 the strap when not extended through the opening.

6. A club carrier comprising a flexible body strip, and club-receiving pockets extending longitudinally of the strip upon one 130

- face thereof and open at their upper ends, the body strip being rollable to provide a tubular structure open at its ends and having the pockets positioned internally thereof and also rollable to position the pockets externally thereof, and means adjacent the edges of said body strip for holding the body strip rolled.
7. A club carrier comprising a flexible body rotatable to form a tubular structure, pockets extending longitudinally of said body and open at their upper ends, a flap foldable to cover the open upper ends of said pockets, means for releasably securing the free end of said flap when folded, means for releasably securing the side edge portions of said body when rolled, and means for securing the body tightly rolled, with the pockets and flap positioned internally and preventing withdrawal of the flap from within the body.
8. The structure of claim 6, having the body strip provided with a flap extending beyond the open upper ends of the pockets
- and foldable to cover the open upper ends of the pockets, fastener means to releasably connect the free end of the flap to the pockets, and fastener straps to be secured about the body strip when rolled with the pockets internally thereof and the cover flap in an operative position.
9. A club carrier comprising a flexible body rollable to provide a compact mass, pockets upon one face of the body extending longitudinally thereof and open at their upper ends, the upper end portion of the body being provided with a flap extending beyond the open upper ends of the pockets and foldable upon itself to cover the upper ends of the pockets, releasable fastener means for the free end of the flap, and a strap carried by the body to be secured about the rolled body, the strap extending about the roll adjacent the fastener means for the flap and having a lockable securing element.

In testimony whereof I have hereunto set my hand.

ENOCH MOORE, JR.
